UNITED STATES PATENT OFFICE.

THOMAS T. LOTHERINGTON, OF HOUSTON, TEXAS.

STENCIL-BRUSH.

SPECIFICATION forming part of Letters Patent No. 237,562, dated February 8, 1881.

Application filed December 30, 1880. (No model.)

To all whom it may concern:

Be it known that I, THOMAS T. LOTHERINGTON, a subject of the Queen of Great Britain, residing at Houston, in the county of Harris and State of Texas, have invented a new and useful Self-Inking Stencil-Brush, of which the following is a full, clear, and exact description, reference being had to the drawings hereto annexed.

10 My invention relates to stencil-brushes used in stenciling cotton-bales and other merchandise, and its object is to provide a self-acting attachment or receptacle for the ink, whereby the brush may be inked in a simple and economical manner.

By the usual method of inking stencil-brushes twice as much ink is applied to the brush as is necessary, and there is consequently a great waste of ink, caused by the excess of 20 the same dripping from the brush, while the time consumed in dipping the brush into the ink is a considerable loss where a large quantity of merchandise is to be stenciled. To overcome these objections I provide a brush 25 having a perforated back and an ink-receptacle attached thereto, said receptacle having an aperture in the bottom, which may be opened for inking the brush by means of a rod attached to a rubber valve and operated by a 30 lever, as hereinafter more fully described.

In the accompanying drawings, Figure 1 represents a longitudinal sectional view of the stencil-brush. Fig. 2 represents a view taken through line $\alpha\alpha$ of Fig. 1.

35 A represents an ink-receptacle of any desirable shape, having a handle, a , at the end of which is an opening, a' , for receiving the ink. In the bottom of this receptacle is an aperture, a^2 , which is closed by the conical 40 rubber valve or stopper C, which projects downward through the opening, and is prevented from being drawn or lifted entirely out by means of wire guards e attached to its bottom. I do not confine myself, however, to 45 one central aperture in the bottom of receptacle, but may provide a number of such, should they be found desirable. The stopper C is attached to a vertical rod, c' , passing up through the receptacle and held in position

by the cylinder B, through a perforation in 50 the top of which the said rod is allowed vertical movement. In one side of the cylinder B is a vertical slot, b , to allow the ink to pass into the cylinder preparatory to passing down through aperture a^2 .

To the upper end of rod c' , which passes out at the top of receptacle, is attached the lever D, pivoted at d and governed by the spring d' . The rod c' is provided with a rubber washer, c^2 , at the upper end, to prevent the accidental 60 escape of ink through the perforation in the top of the receptacle.

On the under side of receptacle A, and attached thereto, is a flange, E, returning upon itself to form the chamber e , and having its 65 lower edge turned outward to form a connecting-surface for the brush. At the sides of flange or wall forming said chamber are perforated projections or fixed nuts, e' , for receiving the screws e^2 , by means of which the brush 70 F is attached to said receptacle. The chamber e is provided with a layer of cotton or textile fabric, e^3 , the object of which is to distribute the ink, as well as to strain it from all 75 impurities.

The brush F is made with vertical perforations f , to allow the ink to drip between the bristles, and is attached to the flange E by means of the screws e^2 . Between the brush and flange is a rubber gasket, G, for securing a close adjustment of the same, held in position by the screws e^2 , and having perforations g in alignment with perforations f in the brush.

It will be seen that with the same hand that 85 holds the receptacle the lever may be operated at will, causing the stopper C to be lifted from the aperture a^2 , while the ink flows down into the chamber e , percolates through the layer of cotton e^3 , drips through the perforations g and f , and thus moistens and prepares 90 the brush for use. By this arrangement the supply of ink to the brush can be so regulated as to avoid waste, while there is no loss of time in inking the brush, as in the usual 95 manner.

What I claim as my invention, and desire to secure by Letters Patent, is—

In combination with the brush F, having a series of vertical perforations between the bristles, the perforated rubber gasket G, flange E, forming the percolating and distributing chamber e, and receptacle A, having handle a, aperture a² in its bottom, conical stopper C, having guards c, slotted cylinder B, rod c',

washer c², and lever D, all constructed and arranged substantially as shown and described, and for the purpose set forth.

THOMAS TURNER LOTHERINGTON.
